ICE TRAY

Sven W. E. Andersson, Evansville, Ind., assignor
to Servel, Inc., New York, N. Y., a corporation
of Delaware

Original application October 27, 1933, Serial No.
695,398. Divided and this application Septem-
ber 19, 1936, Serial No. 101,567

1 Claim. (Cl. 62—108.5)

This invention relates to ice trays or the like for use in household refrigerators, and constitutes a division of my application Serial No. 695,398 filed October 27, 1933.

5 It is an object of the present invention to provide a device for facilitating and simplifying the removal of ice trays after the contents of the same have been frozen.

The invention, together with the objects and 10 advantages thereof, will become apparent from the following description taken in conjunction with the accompanying drawing forming a part of this specification, and of which Fig. 1 is a fragmentary front view of a cooling unit and an ice 15 tray embodying the invention placed therein, and Fig. 2 is a fragmentary sectional view taken on line 2—2 of Fig. 1 illustrating more clearly parts of the device provided on the tray.

Referring to the drawing, an evaporator or cooling unit 10 of a household refrigerator (not shown) is refrigerated in any desired manner. The cooling unit 10 may be provided with one or more tray receiving compartments, only one of which is shown, in which an ice tray 11 is placed 20 for freezing the contents of the same. The tray 11 includes a receptacle body 12, at the front end of which is provided two bent over extended portions or abutments to which a tray front 13 may be secured by bolts or other fastening elements 25 15. This structure is formed at the time of stamping the tray, the material at each side of the tray being cut along the line indicated at 16 in order to provide a triangular reenforcement at each front outer corner of the tray. The tray front 30 13 is formed with a handle or hand-grip portion 14.

The tray 11 rests on the lower horizontal portion or shelf 17 of the cooling unit with the broad flat bottom of the tray in thermal contact with 40 the shelf to provide a good conductive path for removal of heat through the tray and shelf. When the tray is filled with water, moisture on the bottom of the tray freezes and forms an ice bond between the bottom of the tray and the shelf 45 which must be broken in order to remove the tray from the cooling unit.

In accordance with this invention an improved device is provided for breaking the ice bond which is formed between the bottom of a tray and the 50 shelf of a cooling unit upon which it is placed. Referring to Fig. 2, the device shown includes a lever or bar 18 which extends through a slot 19 formed in the hand-grip portion 14 of the tray front and is provided with a curved upper end 20 55 to provide a finger-grip for actuating the device.

The lower end of lever 18 is rounded and eccentrically pivoted to the lower rounded end of a bracket 21 which extends upward and is riveted or otherwise secured to the front wall of the tray body 12. A spring 22, having the upper end 5 fastened to the flange 23 formed at the upper edge of the front wall of the tray body and the lower end secured to the lever 18, serves to maintain lever 18 in the inoperative position shown in Fig. 2.

In the use of the above described device, the tray body 12 is filled with water or other matter to be frozen and inserted in the cooling unit 10 of the refrigerator with which the tray is used. With the tray positioned in the cooling unit heat 15 is removed from the tray bottom through the shelf, due to the production of cold by the cooling unit, whereby any moisture between the tray bottom and the shelf is frozen, thus firmly uniting 20 the parts. When it is desired to remove the tray 25 with its contents, the handle 20 of lever 18 is moved downward whereby the lower rounded end of lever 18 is rotated eccentrically with respect to the lower rounded end of the bracket 21. With such eccentric movement of the lower rounded 25 end of the lever 18 the lower end of the lever bears against the surface of the shelf 17 and exerts a separating force between the tray body 12 and shelf 17. When the ice bond between the tray and shelf is broken and the finger-grip 20 30 is released, the spring 22 returns the parts to the position shown in Fig. 2, whereupon the hand-grip 14 can be grasped and the tray removed from the cooling unit.

In view of the foregoing, it will be seen that 35 an improved device has been provided for facilitating the removal of ice trays from cooling units. The lower rounded end of lever 18 is normally disposed adjacent the bottom of the tray body 12. When a rotating movement is imparted to 40 the lower rounded end of lever 18 by pulling down the finger-grip 20, a portion of the lower rounded end extends beyond the bottom of the tray. With this construction the lower end of the lever 18, together with the bracket 21, forms a leverage 45 means which can be extended whereby sufficient force is provided to separate the tray body from the support.

Although a particular embodiment of the invention has been shown and described, it will be 50 apparent that various modifications and changes may be made without departing from the spirit and scope of the invention.

What is claimed is:

An ice freezing tray having bottom, side, and 55

end walls, a front plate secured to the tray in spaced parallel relation with one of said end walls, said front plate having a vertical slot and being formed to provide a handle for the tray, a lever having one end projecting through the slot in said front plate and the other end pivotally connected to said tray adjacent the lower front edge thereof, a spring for normally holding the

lever against the top of said slot, and the pivoted end of said lever being formed as a cam which engages a tray supporting shelf when rotated by movement of the projecting end of said lever downward in said slot against the action of said 5 spring to loosen any ice bond there may be between the shelf and the bottom of the tray.

SVEN W. E. ANDERSSON.
